UNITED STATES PATENT OFFICE.

EDWARD HANAK, OF HOUSTON, TEXAS.

TRAVELING-CONVEYER TRAY.

Application filed September 1, 1927. Serial No. 216,972.

The invention has for its object to provide a new and improved supporting tray for use on traveling conveyers in supporting cotton bales or the like while being carried by the conveyers, the said trays being constructed to be pendently supported by said conveyer in position for having the bales conveniently deposited thereon from hand trucks, and having thereon means to engage the bales or other articles supported thereon and secure them against inadvertent displacement while being transported, but which are readily removable to facilitate unloading of the bales when desired.

With the above and other objects in view that will hereinafter appear, the invention further resides in the novel details of construction, combination and arrangement of parts, all of which will be first fully described in the following detailed description, then be particularly pointed out in the appended claims, reference being had to the accompanying drawings, in which:—

Figure 1 is a perspective view illustrating the invention in use.

Figure 2 is an end view, the loading of a cotton bale onto the tray being indicated in dotted lines.

Figure 3 is a face view of the tray, the pivoted arms being removed.

Figure 4 is a horizontal section taken just above the base of the tray and looking toward the base.

Figure 5 is a detail vertical cross section of the supporting angle with a hanger bar attached thereto.

Figures 6 and 7 are diagrammatic end views illustrating modified forms of bale securing means.

In the drawings in which like numerals of reference indicate like parts in all of the figures, 1 generally designates a traveling conveyer of any approved type adapted to travel along guide trackways for distributing bales of cotton or similar loads.

Hanger bars 2 are pivotally or pendently connected at 3 to the conveyer and, at their lower extremities, are hooked under an angle iron supporting bar 4 as indicated at 5 and are secured to that bar by rivets or other suitable securing means as at 6.

End standards 7 are secured as at 8 to the ends of the supporting bar 4 to depend therefrom and are suitably braced adjacent their connection with the said bar by the angle braces 9.

At their lower ends the standards 7 are bent downwardly and outwardly as at 10 and cooperate with similarly bent members 11, which are secured thereto as at 12, in supporting a rectangular open tray 13, the lower extremities of the portions 10 and 11 being secured to the tray corners as at 14.

To provide for the desired strength of the tray 13 and for desired economy of manufacture the same is preferably constructed of angle iron bent to form an open rectangle as is clearly indicated in Figures 1 and 4 of the drawings. The corners of the tray are suitably braced and reinforced by the corner plates 15, and to suitably close the open bottom portion of the tray and also to brace the same, cross bars 16 are secured across the base flanges of the angles at spaced intervals as indicated in Figures 3 and 4.

Cleats 17 formed of short lengths of angle iron are secured as at 18 to the opposite faces of the vertical flange portion of the supporting angle 4 at opposite sides thereof and with their extended faces opposed in spaced relation, see Figures 1 and 3. Each cooperating pair of extended flanges of the cleats are apertured to receive a pivot pin 19 upon which is pivoted a load securing arm 20 branched or forked as at 21 toward its free end to form a pair of arm portions each equipped with an inwardly and upwardly directed sharp nose 22 adapted to bite into and assist in securely holding a load upon a tray.

In this disclosure I have illustrated four such securing arms arranged in opposed pairs as is clearly illustrated in Figures 1 and 2 of the drawings. In practice I have found this equipment quite practical but it should be understood that a greater or lesser number of arm pairs may be employed to suit the needs of any particular use of the invention.

The extended flanges of the cleats 17 also serve to mount a stop pin 23 which limits the downward movement, or movement of the arms 20 toward each other, as indicated by the dotted lines to the left of the center of Figure 2.

By referring to Figure 2 of the drawings it will be observed that when it is desired to load a tray with a bale or bales of cotton or any other similar load, the arms 20 at one side are raised in any suitable manner as indicated by the dotted lines to the right of the

center of Figure 2, while the arms at the left remain hanging in the position indicated in dotted lines to the left of the center of that figure. A hand truck bearing the load 5 may then be moved to the position indicated in dotted lines in Figure 2 (to facilitate this the tray 13 is carried closely adjacent and just above the ground line) from which position it may be conveniently tilted over onto the tray to the position illustrated in full lines in the said Figure 2.

As the tilting movement of the bale onto the tray is being accomplished the hook ends 15 22 of the opposed arms, because of their upward and inward direction of projection, will automatically bite into the bale and limit its movement beyond the desired substantially vertical position illustrated. This loading of the bale or bales being completed 20 the formerly raised arms 20 are lowered to cause the sharp noses 22 thereof to bite into the opposed side of the bale and cooperate with the previously engaged arm ends in securely holding the load to position against 25 inadvertent displacement during travel of the conveyer.

When it is desired to remove the load it is, of course, only necessary to lift the securing lugs at a convenient side of the tray to 30 release the bale or bales at that side and render removal thereof possible.

In Figures 6 and 7 of the drawings I have 35 illustrated slightly modified means for securing the bales to position upon the tray. In Figure 6, 24 indicates a fixed abutment secured as at 25 to the supporting angle 4 to project into position for forming a fixed or positive abutment at a suitable position at one side of the tray. The usual pivoted 40 securing arms 20-22 are employed at the opposite side of the tray and cooperate with the said fixed abutment in securing the load to position upon the tray and in providing adjustable receiving space for accommodat- 45 ing varied sizes of loads.

In Figure 7 the same fixed abutment is 50 illustrated at one side of the tray but a modified means of adjustably securing the load at the other side of the tray is provided. In this form of the invention a simple link 55 chain 26 may be employed and may be adjustably connected to the securing hooks 27 carried by the standards 7. In this form when a bale is mounted on the tray 13 with one side thereof against the abutment 24 one link of the chain may be slipped over the hook on one end standard and drawn tightly 60 around the side of the bale and a suitable link at the other end of the chain slipped over the hook mounted on the other end standard. By providing this chain and hook securing means loads of various sizes may be accommodated by utilizing various links in securing the load to position.

65 From the foregoing description, taken in

connection with the accompanying drawings, it is thought that the novel details of construction, the manner of use and the advantages of my invention will be readily apparent to those skilled in the art to which it relates.

What I claim is:—

1. A device of the character described comprising a support bar, means to mount the bar on a conveyer, end standards carried by the bar, a tray carried by the standards, and means independent of said mounting means carried by the bar to engage an article mounted on the tray and secure it against inadvertent displacement. 75

2. A device of the character described comprising a support bar, means to mount the bar on a conveyer, end standards carried by the bar, a tray carried by the standards, and means carried by the bar to engage an article mounted on the tray and secure it against inadvertent displacement, said engaging means constituting at least one pivoted arm having a sharpened nose to engage 85 said article being carried.

3. A device of the character described comprising a support bar, means to mount the bar on a conveyer, end standards carried by the bar, a tray carried by the standards, and means carried by the bar to engage an article mounted on the tray and secure it against inadvertent displacement, said engaging means constituting at least one pivoted arm having a sharpened nose to engage 95 said article being carried, and means to limit the movement of the arm. 100

4. A device of the character described comprising a support bar, means to mount the bar on a conveyer, end standards carried by the bar, a tray carried by the standards, and means carried by the bar to engage an article mounted on the tray and secure it against inadvertent displacement, said engaging means constituting at least one pivoted arm having a sharpened and inwardly- 105 upwardly turned nose to engage said article 110 being carried.

5. A device of the character described comprising a support bar, means to mount the bar on a conveyer, end standards carried by the bar, a tray carried by the standards, means carried by the bar at one side to engage the article being carried at that side, and adjustable means to engage the article being carried at its other side and hold it against said first mentioned engaging 115 means. 120

6. A device of the character described comprising an angle iron support bar, means to pendently mount the angle iron bar on a conveyer, end standards depending from the ends of the bar, braces to brace the standards, a rectangular tray to support the article being carried, said standards being secured to said tray at its ends to support 125 130

the same adjacent but above the ground, and means at each side of the support bar and bearing adjustable spaced relation to engage articles being carried and secure them against inadvertent displacement.

7. A device of the character described comprising a support bar, means to mount the bar on a conveyer, end standards carried by the bar, a tray carried by the standards, 10 and article securing arms pivoted to each side of the support bar and including inwardly-upwardly directed sharp noses to bite into the articles being carried and secure them to position on the tray.

8. A device of the character described comprising a support bar, means to mount the bar on a conveyer, end standards carried by the bar, a tray carried by the standards, and article securing arms pivoted to each 20 side of the support bar and including in-

wardly-upwardly directed sharp noses to bite into the articles being carried and secure them to position on the tray, and means to limit movement of the arms toward each other.

9. A device of the character described comprising a support bar, means to mount the bar on a conveyer, end standards carried by the bar, a tray carried by the standards, and article securing arms pivoted to each 25 side of the support bar, each said arm being forked at its free end to provide two arm portions spaced relatively distant from each other, and each said arm portion including an inwardly-upwardly directed sharp nose to bite into the article being carried to cooperate with the remaining arm portion noses in securing said articles to position on the tray.

EDWARD HANAK.
